UNITED STATES PATENT OFFICE.

HENRY G. O'NEILL, OF LOUISVILLE, KENTUCKY, ASSIGNOR TO THE STANDARD REGISTER COMPANY, OF BOSTON, MASSACHUSETTS.

CASH REGISTER AND INDICATOR.

SPECIFICATION forming part of Letters Patent No. 480,122, dated August 2, 1892.

Application filed November 3, 1891. Serial No. 410,743. (No model.)

To all whom it may concern:

Be it known that I, HENRY G. O'NEILL, a subject of the Queen of Great Britain, and a resident of Louisville, in the county of Jefferson and State of Kentucky, have invented certain new and useful Improvements in Cash-Registers; and I do declare the following to be a full, clear, and exact description of the invention, such as will enable others skilled in the art to which it appertains to make and use the same, reference being had to the accompanying drawings, and to letters of reference marked thereon, which form a part of this specification.

Figure 1 of the drawings is a vertical section taken on line $\alpha\alpha$, Fig. 3. Fig. 2 is a top plan view, partly in section. Fig. 3 is a front elevation with the key-levers in section. Fig. 4 is a top plan detail view of the fluted roller, adding-wheels, and gear.

This invention has relation to cash-registers or accounting-machines; and it consists in the construction and novel combination of devices constituting mechanism whereby the cash transactions of such machines may be summed up, as hereinafter shown and described.

The invention particularly relates to that class of machines shown and described in my application filed October 31, 1891, Serial No. 410,515, differing therefrom in the following particulars. In the said application the adding-wheels are arranged in series, periphery to periphery, the first of the series having a bevel gear-wheel actuated directly by a fluted shaft operated upon by the key-levers, each wheel having a spur or spurs operating upon the succeeding wheel to effect the carrying.

In the present application adding-wheels are arranged on a common shaft in parallel order and are provided with a series of carrying-pinions on a separate shaft. The movement of the key-levers is transferred to the adding-wheels through the fluted shaft, a series of idler-wheels in gear with a pinion on the adding-wheel shaft, and through the carrying devices.

In the accompanying drawings I have illustrated the invention in connection with a simple machine having ten keys marked for five cents, ten cents, &c., up to sixty cents; but it is obvious that it may be employed in

machines having a greater number of keys, as the principle of construction would be the same.

The letter A designates the key-levers, which are pivoted at a and provided with a transverse pressure-bail B, common to all, which is actuated by a spring b to cause these key-levers to return to their normal positions after action. Each key-lever is provided with an arc rack C, in the form of an arm, extending therefrom in the vertical plane at or near its end. The arc rack is radially centered at the axes of the key-lever, as indicated, and is designed to engage a fluted shaft, toothed cylinder, or roller D, which extends transversely and is common to all the keys. The number of teeth in the arc rack of each key-lever corresponds to the denomination or value of the key, one tooth being provided for the five-cent key, two teeth for the ten-cent key, &c. In the illustration the ten teeth of the fifty-cent key are shown on its arc rack. When the key is depressed, its rack-arm engages and turns the fluted roller or shaft through an arc corresponding to the number of teeth in the rack of the key operated.

Loosely journaled at the end of the fluted roller or shaft is a toothed wheel E, which has a pawl-and-ratchet connection with said fluted roller or shaft in order that it shall turn with said roller or shaft when the latter is operated by any key-lever, but will not be revolved backward by the reverse movement of said roller or shaft when the key-lever is returning to its normal position. The toothed wheel E is in engagement with the idle-wheels e' and e'' , whereof the latter engages the pinion g of the first adding-wheel G of the series, and when any key is operated its arc rack will actuate the fluted shaft or roller, and thereby turn the gearing and the adding-wheel G sufficiently to cause its value to be added to the amount indicated by the series of adding-wheels. The adding-wheel G is marked around its periphery with the figures "0" and "5" alternately at regular intervals and is provided with a carrying-pinion g' in rear, said pinion being journaled on a bail-frame K and having sufficient breadth to engage the teeth of the next wheel when the 5-mark has passed.

the reading position. The other adding-wheels H of the series are marked around their peripheries with the figures "1" to "9" and "0" at regular intervals, and are each 5 provided with a carrying-pinion h to engage the pinion of the next wheel when the 9-mark has passed its reading position.

The train of gearing will provide sufficient 10 friction to prevent any backward turning of the toothed wheel E at the end of the fluted shaft or roller. Nevertheless, the adding-wheels may be readily moved whenever it is desired to reduce the set to "0"—that is to say, 15 to bring all said wheels into position with their 0-marks in the reading position. In preparing for this reduction the angular bail-frame K, which carries the carrying-pinions, is turned backward, disengaging these pinions and bringing the stop bail-bar K' against 20 the peripheries of the adding-wheels in position to engage their stop-pins k, which serve to stop their movements when their 0-marks are brought to the reading position. The stop-bail branch of the angular frame is then 25 moved away from the adding-wheels, and this action brings the carrying-pinions to their position of engagement with said wheels.

This adding mechanism is of compact character and may be readily employed in connection with indicating or display apparatus 30 and key-regulating devices of various kinds.

I have illustrated indicating values at I and key-regulating devices at J and V; but as these form separate inventions, for which 35 I have made other applications for patents, it is unnecessary to enter into any detailed explanation of the same in this specification.

Having described this invention, what I claim, and desire to secure by Letters Patent, 40 is—

1. In a cash-register and accounting-machine, the combination, with the key-levers and their arc racks having, respectively, teeth corresponding in number to the required action of the key and the fluted shaft or roller 45 operated upon by said teeth and having thereon a loose toothed wheel connected thereto by a pawl and ratchet so arranged that said wheel is carried with the shaft during the forward movement of the latter, but is held stationary during its backward movement, of the series of adding-wheels arranged upon a shaft parallel with said fluted roll and alongside thereof, the pinion thereon, the carrying devices, and the idler-wheels for transmitting the movement of said shaft to the adding-wheel shaft, substantially as specified. 55

2. In a cash-register and accounting-machine having a fluted shaft or roll acted upon by an arc rack on the key-levers and carrying a pinion loosely thereon and connected thereto by a pawl-and-ratchet device so arranged that said wheel is revolved with the shaft during its forward movement, but permits the shaft to turn loosely thereon during its backward movement, the combination therewith of the adding-wheels arranged side by side upon a shaft and alongside thereof parallel with said fluted shaft, the idler-wheels in gear with said loose wheel and with the pinion of 70 the first adding-wheel, and the series of carrying-pinions for the adding-wheels, said pinions being journaled on a movable frame, substantially as specified.

In testimony whereof I affix my signature in 75 presence of two witnesses.

HENRY G. O'NEILL.
